United States Patent Office

Des. 217,333
Patented Apr. 28, 1970

217,333

COMBINED BOTTLE AND OVERCAP THEREFOR

Richard L. Weckman, Perrysburg, Ohio, assignor to Owens-Illinois, Inc., Toledo, Ohio, a corporation of Ohio

Filed Feb. 19, 1969, Ser. No. 15,831

Term of patent 14 years

Int. Cl. D9—01

U.S. Cl. D9—44

FIG. 3

FIG. 1

FIG. 2

FIG. 4

FIG. 7

FIG. 6

FIG. 1 is an elevational view of a combined bottle and overcap therefor showing my new design.

FIG. 2 is an end elevational view taken from the right side of FIG. 1.

FIG. 3 is an end elevational view taken from the left side of FIG. 1.

FIG. 4 is a top plan view thereof.

FIG. 5 is a view similar to FIG. 2 showing the bottle with the cap removed.

FIG. 6 is a view similar to FIG. 1 showing the bottle with the cap removed.

FIG. 7 is a view similar to FIG. 4 showing the bottle with the cap removed.

The sides opposite those seen in FIGS. 1 and 6 are mirror images of the respective sides shown.

I claim:

The ornamental design for a combined bottle and overcap therefor, substantially as shown and described.
